EMIL KRENZLER, OF BARMEN, GERMANY

LACE-BRAIDING MACHINE

Application filed March 28, 1929, Serial No. 350,463, and in Germany January 30, 1929.

In single thread braiding machines in which the intermittently driven driver plates are secured against rotation when in their position of rest in the track plate by locking means, and in which no spring pressure or other upwardly directed thrust is exerted upon the driver plates, it is known to mount these plates on their supporting columns without the use of securing nuts or screws or like fastening means so that they are free for upward movement on the columns to permit of their ready detachment when desired.

However, in that type of braiding machines in which the driver plates are secured against rotation in their position of rest by locking means exerting upwardly directed spring pressure on the driver plates, the above-described way of mounting the plates cannot readily be employed, because of the upwardly directed pressure of the locking members against the driver plates, whereby said driver plates would be lifted out of working position. It is for this reason that in all machines of this character hitherto constructed, the driver plates were provided with openings for the upward passage of the upper ends of the columns on which the driver plates were secured by nuts screwed onto the upper ends of the columns, and which were usually counter-sunk in grooves of the plates, which nuts had to be removed whenever it was desired to remove a driver plate. The spring pressure referred to may be that, as shown in the present instance, exerted by the spring which retracts the movable member of the clutch which connects the driver plate with or disconnects it from its driving shaft.

This way of mounting and removing the plates is, of course, rather complicated and expensive, and takes up valuable time. The use of securing nuts, moreover, calls for driver necks of a comparatively large diameter, which in its turn reduces correspondingly the diameter of the lower foot plates of the bobbins, and also has the disadvantage that oil and dirt can readily accumulate in the recesses of the driver plates containing the nuts, from which the oil made impure by the dirt will then ooze through between the nut and plate to the bearings.

The present invention refers to a machine of the latter-named kind, i. e., a braiding machine in which the driver plates are arranged in the track plate and rotated only when required, and in which the plates are secured against rotation in their position of rest, i. e. normal position, by spring actuated locking arms which engage in notches provided at the lower side of the driver plates or safety (securing) plates rigidly connected thereto. The object of the invention is to overcome the above-described disadvantages in machines of this character hitherto employed by providing means which prevent the driver plate from being upwardly displaced under the pressure of the locking arms except when the driver plate is in a prescribed position with respect to its normal position and also with respect to other driving plates such as to permit of its upward displacement and removal. By the use of the present invention the driver plate is made readily removable though it is no longer necessary to secure the driver plates to the columns by means of nuts or screws or other means, notwithstanding the use of spring actuated clutch and locking members. According to the present invention the driver plates are mounted on the columns in such manner that they can be removed in upward direction without releasing any fastening means whatsoever, but in order to prevent casual displacement of the driver plates, because of the spring pressure of the locking arms, the driver plates are secured against upward displacement by means of projections (which co-operate with the track plate or the columns) in all such positions in which they are under pressure of the spring actuated locking arms, particularly when in their position of rest, and except when in the prescribed position referred to.

As may be seen, in the new machine the insertion and exchange of a plate is very easy and simple, since the plates can be inserted in the machine and again removed—for example in a position which is displaced by 90° from the position of rest—without the necessity for any nuts or screws whatsoever to be unscrewed and again screwed up. A further considerable advantage is that the necks of

the driver plates can be of smaller diameter than hitherto or may be provided at the upper ends with lateral apertures for the entry of the foot discs or flanges of the bobbins. Consequently the lower flanges of the bobbins may be of greater diameter than hitherto and may even be made of the same diameter as the upper bobbin flanges. It is even possible with the new construction to make the bobbin flanges correspond with the pitch of the machine, that is to say to make them of the largest possible diameter. Finally the recesses for the reception of the nuts are omitted so that the collection of oil and dirt is avoided. The plates also need not be bored right through to the upper surface, and the bore of the neck can be closed on top. The plates therefore have an unbroken surface except for the driving notches, so that oil which has been contaminated by dirt cannot penetrate through to the bearings.

With the new arrangement of the driver plates, it is advisable to relieve the plates as far as possible from the pressure of the spring for disconnecting the couplings. Therefore, according to the invention, the pressure which is applied to the coupling in order to disconnect it is, during the first stage of the process of disconnection, no longer taken as hitherto by the locking members and the driver plate, but by a fixed part of the machine which is independent of these parts. This can be effected by providing on the column a collar having two oppositely situated notches and on the coupling sleeve two oppositely situated lugs which co-act with this collar. Then, as soon as it is released by the jacquard gear, the coupling is supported with its lugs against the collar so that the locking member does not yet abut against the driver plate or the safety plate which is connected thereto. Only when the semi-rotation of the plate is ended and disconnection is completed with the passage of the lugs through the notches in the collar, is pressure applied to the plate by the stop provided on the adjusting fork of the coupling sleeve engaging in a groove in the driver plate or in the safety plate. Then however the plate is situated in its position of rest in which it is secured against axial displacement by its projections engaging under the track plate. This arrangement has the further advantage that the locking members, do not, as was hitherto the case, grind against one another in the first stage of the process of disconnection, which caused an unnecessary wear on these parts.

Various constructional embodiments of the invention are illustrated by way of example in the accompanying drawings, in which

Fig. 1 is an approximately radial section on the line 1—1 of Fig. 2 of a machine according to the first example,

Fig. 2 is a plan thereof.

Fig. 3, a detail in horizontal section on the line 3—3 of Fig. 1,

Fig. 4 is a radial section of a machine according to the second example,

Fig. 5 a plan thereof,

Fig. 6 shows a modification of the driver plate in section, this section being taken at an angle of 90° to the section in Fig. 1,

Fig. 7 is a further constructional form of the driver plate in plan,

Fig. 8 is a section of the line 8—8 of Fig. 7 and,

Fig. 9 is a view looking in the direction of the arrow 9 and Fig. 7.

Referring to the drawings, 8 is the track plate and 9 are the driver plates which are arranged in the apertures in the track plate and are revolubly mounted at the upper ends of the stationary columns 10. Below each driver plate 9 the columns 10 carry a continuously rotating driving wheel 11. The upper side of this wheel is provided with coupling claws 12 with which the coupling claws 13 of a sleeve 15, which is displaceable on the hollow stem 14 of the driver plate 9 but is not revoluble thereon, co-act. The coupling sleeve 15 is adjusted by means of a fork 16 which is fitted on a rod 18 which is carried vertically in the track plate 8 and in the base-plate 17. The rod 18 is moved into its upper end position in which the driving wheel 11 is disconnected from the driver plate 9, by means of a spring 19. It can be moved downwards to effect the coupling against the action of the spring by means of the jacquard gear through the agency of a rod which is not illustrated in the drawing. The adjusting fork 16 is provided with a stop or arm 20 which, when the coupling is disconnected, engages in one or the other of two grooves 21 provided in the under side of the driver plate 9 and thus holds the driver plate against rotation in its position of rest.

In contradistinction to the known machines, the internal bores of the hollow stems 14 of the driver plates 9 do not extend right through the plates 9 but are closed at the top. The driver plate 9 therefore has no apertures except the two opposite notches 22 at the edge, which serve the purpose of guiding and taking the bobbins, so that it has an otherwise unbroken, even surface. There are no nuts or releasable fastening means for the driver plates. The driver plate is simply inserted from above in the track plate 8 of the machine and on the column 10 so that its stem 14 engages the upper portion of the column 10 and rests on a shoulder of the column 10 and is thereby supported on the column at the required height so as to be normally free for upward and downward sliding movement on the column, the column being free from projections or fastening means prohibiting such movement of the driver plate. On the under sides of the driver plate

9 there are provided two oppositely situated radial projections or lugs 23, which engage under the edge of the aperture in the track plate 8. The projecting parts of the lugs 23 are so shaped and dimensioned, that the notches 22 of adjacent plates allow the lugs of a plate which has to be inserted in or taken out of the machine at any time to pass. Thus the driver plate can be inserted in the machine and again removed therefrom in positions displaced by 90° from its positions of rest, without the necessity for releasing any fastening means whatsoever. As soon, however, as the lugs 23 engage under the edges 15 of the aperture in the track plate 8—and this occurs during the greater part of the rotation of the driver plate and especially when the diver plate is in its position of rest—the plate 9 is secured against upward movement 20 by the lugs 23. The pressure exerted by the disconnecting spring 19 through the stop 20 on the driver plate cannot therefore lift up the plate. If, however, the driver plates are turned to shift a driver plate to a position 25 at an angle of 90° displaced in its path of rotation from its rest position, the projections 23 of this shifted plate will underlie or register with the recesses 22 of adjacent driver plates at opposite sides thereof, as 30 shown by the upper drive plates in Figs. 2 and 5, whereupon such shifted driver plate may be freely removed. It is however not necessary that they should then be secured in this manner because the foot discs or flanges of the bobbin which simultaneously overlap the track plate 8 and the driver plate 9 both on top and underneath prevent an upward movement of the plate.

In addition means may be provided for relieving the driver plate from the pressure of the disconnecting spring during its rotation. For this purpose in the constructional example there is arranged on the column 10 below the stem 14 a band or collar 24 having 45 two oppositely situated cut out portions or notches 25, and two oppositely situated inwardly projecting lugs 26 are fitted to the claws 13 of the coupling sleeve 15 in such a manner that they are able not only to engage under the collar 24 on the column but also to pass through the notches 25 in the collar. When the coupling is disconnected and the driver plate 9 is arrested in its position of rest the lugs 26 of the coupling sleeve 15 are 50 situated vertically above the notches 25 in the collar 24. When the coupling is engaged—as usual with the simultaneous release of the driver plate 9 by the arm or stop 20—the lugs 26 pass through the notches 25 below the collar 24 and move below the collar during the rotation of the driver plate. If the sleeve 15 is released by the jacquard gear after a certain angular rotation of the driver plate, it then moves upwards under the influence of the spring 19. This movement is

limited however by the lugs 26 striking the collar 24, before the stop 20 comes into engagement with the driver plate 9. The pressure of the disconnecting spring 19 is thus taken by the collar on the column independently of the locking member and of the driver plate. When the semi-rotation of the plate is completed the lugs 26 are under the notches 25 of the collar 24 and the sleeve 15 can move into the position of disconnection under the influence of the spring 19, whereby the driver plate 9 is secured in its position of rest by the engagement of the arm or stop 20 in one of the grooves 21. As is clear, with this arrangement the first step in the process of disconnection relieves the driver plate from the pressure of the spring 19. Pressure is only applied to the driver plate by this spring when the driver plate is stationary.

The example illustrated in Figs. 4 and 5 differs from that of Figs. 1-3 in that there is carried by and arranged below the driver plate 9 an extension of said plate in the form of a safety plate 27 which is rigidly connected therewith. Also the lugs 23 which prevent the driver plate 9 from being lifted up are formed by radial projections of the safety plate 27, so that no separate lugs need be fitted to the driver plates itself. Otherwise the arrangement and method of operation are the same as in the example illustrated in Figs. 1-3.

Figs. 4 and 5 also show a particularly simple construction of the safety plate extension 27. Since the stop or arm 20, owing to the spring pressure being taken by the collar on the column 10, does not come into engagement with the driver or safety plate in the first stage of the process of disconnection, the safety plate need no longer be circular as hitherto, and it may instead be in the form of a strip extending in the diametral direction of the driving plate, as may be seen in particular from Fig. 5, with the result that the mass to be accelerated and again retarded at each rotation of the driver plate is reduced.

The new arrangement of the driver plates, has the advantage, in addition to the easy insertion and removal of the plates already mentioned, that with the exception of the notches 23 for guiding and taking the bobbins, the driver plates are closed and can have an unbroken, even surface. Further the considerable advantage is also present that the lower foot discs or flanges of the bobbin, which have hitherto had to be smaller than the upper discs can be increased in size. Then, owing to the omission of nuts for holding the driver plates 9 on the columns 10, their necks 14—at least at their upper ends—can be of smaller diameter than in the known machines and can be provided if necessary with an annular groove or with lateral grooves or notches 28 into which the

lower flanges of the bobbins project as shown in Fig. 6. As may also be seen from this figure, it is possible in this manner to make the lower flanges 29 of the bobbins considerably larger than hitherto, and they may in fact be of the same size as the upper flanges. The invention therefore enables the bobbin discs or flanges, and even the lower flanges, to be of a diameter which is equal or nearly 10 equal to the pitch of the machine. Figs. 7-9 show an example of this.

In these figures the neck 14 of the driver plate is not directly fitted to the driver plate but to the safety plate 27 which is either 15 rigidly connected to the driver plate or preferably, is integral therewith and, is in the form of strip extending across the plate in the direction of its diameter similarly as in Figs. 5 and 4. Or, in other words, the 20 neck 14 is connected with the driver plate 9 by means of strip which is provided below the latter and runs in the direction of its diameter. The strip also contains grooves 21 for the engagement of the arm or stop 25 20 and is provided along each of its longer sides with a groove 31, the inner boundary of which is in the shape of a circular arc, in which the lower flanges 29 of the bobbin engage. The two grooves 31 meet at the 30 centre line of the strip 27 or cut into one another so that a passage 32 which extends right through the strip 27 is formed there and the strip 27 has more or less the form of a bridge. As may be seen it is now possible 35 to make the lower flanges 29 so large that the flanges of the two bobbins located on the same plate nearly touch. The diameter of the flanges 29 is then nearly equal to the distance between the centres of adjacent driver 40 plates. Of course the upper flanges 30 are also increased in size to correspond with the lower flanges 29.

The invention is not limited to the constructional examples illustrated, and other 45 forms of construction are possible within the spirit and scope of the invention as defined in the appended claims.

Claims:

1. In a single thread lace braiding machine, the combination of a track plate having openings therein, a column arranged below each track plate in axial alinement with each opening therein, an intermittently rotatable driver plate operating in each 50 opening in the track plate and slidably and rotatably mounted on the column in alinement therewith, a drive gear, means movable in one direction or the other to connect the driver plate with the drive gear or to disconnect the driver plate from the drive gear and lock said plate from rotation, said driver plate being free for upward movement on the columns and removal therefrom and from its opening in the track plate when in 55 a prescribed position in its path of rotation

displaced from its position of rest, and means operative to hold the driver plate from upward movement and displacement while being rotated and in its position of rest and to release it for upward movement and removal when in such prescribed position. 70

2. In a single thread lace braiding machine, the combination of a track plate having openings therein, a column arranged below the track plate in axial alinement with each of said openings, an intermittently rotatable driver plate movable in each opening in the track plate and slidably and rotatably engaging the column disposed in alinement therewith, a drive gear, means movable in one direction to couple the driver to the drive gear for rotation therewith and movable in the opposite direction to disengage the driver plate from the driver gear and lock said driver plate from rotation in its position of rest, the driver plate being slidably removable from the column without interference when in a prescribed position in its path of rotation displaced at an angle of 90° from its position of rest, and locking means operative in the rotation of the driver plate to lock said driver plate against upward movement and displacement when rotating and when in its position of rest and to release it and permit of its removal when in such 95 prescribed position. 90

3. In a single thread lace braiding machine, the combination of a track plate having an opening therein, a column arranged beneath the track plate and in axial alinement with each opening, an intermittently rotatable driver plate movable in each opening and having a sleeve member depending therefrom and slidably and rotatably engaging the alined column, the latter terminating at its upper end in said sleeve below the top of the driver plate, a drive gear, means movable in opposite directions for coupling the driver plate to the drive gear for rotation therewith and releasing said plate and locking it against rotation in a position of rest, and means for locking the driver plate against upward movement and displacement on the column while rotating and in its position of rest releasing it for upward movement and detachment from the column and track plate without interference when said driver plate is in a prescribed position in its path of rotation displaced from its position of rest. 100 105 110

4. In a single thread lace braiding machine, the combination of a track plate having openings therein, columns arranged below the track plate and in axial alinement with said openings, intermittently rotatable driver plates movable in the openings and having sleeves depending therefrom and slidably and rotatably engaging said columns, a drive gear, a clutch for coupling the driver plate to the drive gear for rotation therewith, a locking member for locking the 115 120 125 130

driver plate against rotation, an element movable in one direction for throwing the clutch into action and releasing the locking member, a spring for moving said element in the opposite direction to release the clutch and move the locking member into position to lock the driver plate against rotation in its position of rest, and locking means for locking the driver plate against upward movement and removal from the opening in the track plate when said driver plate is rotating and in its position of rest and releasing said driver plate and permitting of its upward movement and removal when the driver plate is in a prescribed position in its path of rotation displaced from its position of rest.

5. In a single thread lace braiding machine, a track plate having intersecting openings, 20 columns, arranged below said openings, and in alinement therewith, intermittently rotatable driver plates movable in the openings and each having oppositely arranged edge notches, said driver plates being rotatably 25 and slidably mounted on the columns, a drive gear for each driver plate, means for coupling each driver plate with its drive gear for rotation therewith or disconnecting the driver plate and locking said plate against rotation, 30 and projections on each driver plate normally underlying the track plate to hold the driver plate from upward movement and displacement when rotating, the arrangement of the said projections on each driver plate being 35 such that when the driver plate occupies a prescribed position in its path of rotation displaced from its position of rest said projections will register with the notches of adjacent driver plates whereby the driver plate is left free to be moved upwardly and detached.

40 6. In a single thread lace braiding machine, the combination of a track plate having openings therein, a column arranged below and in axial alinement with each opening, an intermittently rotatable driver plate arranged for operation in each opening in the track plate and mounted to slide vertically and to rotate horizontally on the column in said 45 opening, a drive gear, means for coupling the driver plate to the drive gear to rotate therewith and releasing it from the drive gear and locking it from rotation, and means for locking the driver plate from upward movement 50 on the column except when said plate is in a prescribed position in its path of rotation, the aforesaid means for locking the driver plate from rotation and from upward movement being arranged entirely below the plane 55 of the upper surface of the track plate and the driver plate being free for upward sliding movement on the column without interference from said locking means when disposed in such prescribed position.

65 7. A single thread lace braiding machine

embodying a track plate having openings therein, a column arranged below each opening in the track plate, an intermittently rotatable driver plate arranged in each opening in the track plate, a stem depending from the driver plate and rotatably and slidably mounted on the column, a drive gear mounted on the support, a clutch member movably mounted between the driver plate and gear for engagement with and disengagement from the gear, a locking element engageable with the driver plate to hold the same from rotation when said plate is in its position of rest and the clutch member is disengaged from the gear, a control device spring actuated in one direction to disengage the clutch from the drive gear and engage the locking element with the driver plate and pressure actuated in the opposite direction to engage the clutch member with the gear and disengage the locking element from the driver plate, locking means for holding the locking element from engagement with the driver plate when the driver plate is rotating and releasing the locking element from engagement with the driver plate when said driver plate is at rest, and means for locking the driver plate from upward displacement on the column when in a position of rest and releasing the driver plate for upward displacement and removal from the column when shifted to a prescribed position at an angle in its path of rotation to its position of rest.

In testimony whereof I affix my signature.
